UNITED STATES PATENT OFFICE.

HENRY J. TOEPFERT, OF HOLYOKE, MASSACHUSETTS, ASSIGNOR TO WHITE AND WYCKOFF MANUFACTURING COMPANY, OF HOLYOKE, MASSACHUSETTS, A CORPORATION OF MASSACHUSETTS.

METHOD OF LINING ENVELOPES AND MACHINE.

Application filed March 14, 1927. Serial No. 175,166.

The present invention relates broadly to paper fabricating mechanism, and more especially to a machine for attaching liners to envelope blanks at a high rate of speed.

5 The machine comprises the following groups of mechanism: envelope blank stack feeding mechanism; mucilage applying mechanism; devices to feed individual envelope blanks to an assembly table; mechanism to position the envelope blank on said assembly table; devices to support the stacks of liners on each side of the assembly table and to feed from alternate stacks to said assembly table, thereby applying a liner from 10 one stack to the envelope blank while a liner is being picked up from the other stack, and consequently, greatly increasing the speed of 15 the machine; and pressure applying mechanism to squeeze the attached blank and liner 20 together as a unitary article.

One of the objects of the present invention is to facilitate the rapid and accurate feeding of envelope blanks by means of ball bearing tracks and traveling tapes, which 25 grip the margins of the blank and permit the same to be carried rapidly forward without curling the edges, etc. due to wind resistance.

Another object of the present invention is 30 the speeding up of the applying of liners to envelope blanks by providing a plurality of stacks of blanks and then feeding liners in succession from said stacks.

A further object of the present invention 35 is to facilitate the automatic maintenance of top level of the envelope blanks and the liner stacks and at the same time to provide a resilient cushion against which mechanism operating on said stacks may be 40 resisted.

Other and further objects of the present invention will in part be obvious and will in part be pointed out hereinafter in the specification following by reference to the 45 accompanying drawings forming a part hereof; and throughout the several figures thereof like characters are used to represent like parts.

The disclosure herewith is a complete 50 compliance with the requirements of the patent statutes however, it is realized that

the inventions may be embodied in and practiced by constructions other than those specifically shown and described, and therefore, the present disclosure is to be understood as illustrative and not in the limiting sense. 55

Fig. 1 is a general plan view of the machine with a few parts broken away to illustrate the underlying structure. 60

Fig. 23 is a view of the cam for controlling the suction upon the other liner carrier roller.

Fig. 24 is a plan view of one of the liner carrier rollers.

Fig. 25 is a view comprising a longitudinal section of one end of the roller shown in Fig. 24.

Figs. 26, 27, and 28 are respectively sections upon section lines 26, 27, and 28 of Fig. 23.

Fig. 29 is a diagrammatic view illustrating the pneumatic controls comprising valves, etc., for the pneumatic system of the machine.

The machine preferably comprises a front main frame 1 and a rear main frame 2. Power is applied to the machine (Figs. 1 and 4) through a belt wheel 4 loosely mounted on the main shaft 5 and adapted to be operatively connected therewith to drive the same through a manually controlled clutch 6. The power delivered to the main shaft is distributed throughout the operating elements of the machine by suitable groups of mechanism to cause the blanks and liners to be assembled and cemented together as a unit.

Envelope blank stack support.

Referring more especially to Figs. 1 to 5 inclusive, a stack of inverted envelope blanks A rests upon a shelf 7 which is carried by a head 8 that is secured to the upper end of a column 9 which is vertically slidable through a guiding sleeve 10. The guiding sleeve 10 is carried by an inverted U-shaped frame 11 that is secured to the under portion of the front bed plate 12. A link 14 (Figs. 2 and 4) is secured at one end to the head 8 and at the other end to a lever arm 15 which is pivoted upon the depending bracket 16. An angle arm 17 is carried by the lever arm 15 and comprises a means of attachment for the long coiled spring 18 which is anchored to the under portion of the front bed plate 12 and to the outer end of the angle iron 17. This long coil spring 18 comprises an effective counter-balance having a relatively long range of movement, and substantially counter-balances the weight of the shelf 7,

the head 8, and the vertical column 9. A tapered coiled spring 19 is set at its lower end on a rocking base 20 carried by adjustable support 21 on the depending bracket 16 and is provided with a guide rod 22 that is pivoted to the lever arm 15. The upper end of the tapered coil spring 19 bears against an adjustable nut 24 on the guide rod 22. This spring is adjustable to counter-balance the load of the stack of envelopes to be placed upon the shelf 7. The spring suspension for the envelope shelf and connected parts is such that the shelf 7 with the stack of envelopes thereon is normally tended to be lifted, that is, the strength of the springs 18 and 19 and their effective operation is such that the vertical column 9 will slide upwardly through the guiding sleeve 10 unless this movement is restrained. The long spring 18 is a convenient means of applying additional spring forces to the lever arm 15 and acts merely supplemental to the tapered spring 19 so that by using a heavier tapered spring 19, the long coil spring may be dispensed with although a more delicate adjustment may be obtained by the use of the two springs. The front of the column 9 is provided with a rack of ratchet teeth 25 having the faces thereof toward the shelf. A dog 26 carried by the guiding sleeve 10 normally engages the ratchet teeth in the rack 25 and prevents the springs 18 and 19 from lifting the envelope shelf and stack of envelopes thereon. This dog is controlled in such manner as to be released at the proper time (as hereinafter described) to permit the springs 18 and 19 to feed the stack of envelopes in an upward direction. A hand lever 27 is secured to the bottom portion of the column 9 and is pivoted (Fig. 2) to an oscillating link 28 so that the height of the shelf 7 may be manually adjusted to place thereon a new stack of envelope blanks after the blanks on the shelf have been exhausted. A downward pressure on the handle will cause the dog 26 to pass over the teeth of the ratchet 25 therefore a downward movement is effected by merely depressing the handle. An upward movement of the shelf 7 may be accomplished by manually withdrawing the dog 26 from the ratchet teeth 25 and permitting the handle 27 to move upwardly against the action of the springs 18 and 19.

A dog operating lever 29 is fastened upon a shaft 30 which passes through the guiding sleeve 10 and is adapted to operate the dog 26, so that when the dog operating lever 29 is oscillated in a counter-clockwise direction (Fig. 2) dog 26 is removed from the teeth of the ratchet rack 25, thereby permitting the springs 18 and 19 to raise vertical column 9 and the envelope shelf 7. This movement, however, is restrained by the cement applying head and also by the blank feed devices as will be later explained. The

lower end of the column 9 is provided with a rubber bumper 31 to take the shock when the stack is exhausted.

Mucilage applying mechanism.

Referring to Figs. 1 to 5 inclusive, the mucilage or cement applying mechanism comprises a mucilage tank 101 mounted upon the right side of the arch frame 102 (Fig. 4). This tank carries the pick-up roll 104 which runs in a bath of mucilage or cement, the depth of which is regulated by a gate operated by thumb screws 105. The pick-up roll is mounted upon shaft 106 which carries a pinion 107 that cooperates with the drive pinion 108 on the shaft 109 rotatably mounted in bearings 110. This shaft 109 is provided with a belt pulley 111 whereby the shaft is driven by a belt 112 that leads from belt drive pulley 114 on the main shaft 5. This shaft 109 carries on its outer end a hand wheel 115 by means of which the pick-up roll 104 may be manually turned when starting the machine, or for cleaning or other purposes, as is desired. A carriage (Figs. 4 and 5) comprising sleeves 116 and 117 are mounted to slide upon guide rails 118 and 119 that are suspended from cross arms 120 and 121 secured to the under side of the arch frame 102. The supports 122 extending from the cross arms 120—121 to the guide rails 118—119 are adjustable so that the vertical height of the guide rails 118—119 may be adjusted as desired. The sleeves 116—117 are connected by a rod 124 upon which a tubular shaft 125 may have a slidable and also a rotatable movement. This tubular shaft is provided near the central part with a contact ring 126 which is adapted to contact with an inclined cam face on guide arm 127 on one side of the envelope blank shelf 7 and with the oppositely inclined face on guide arm 128 on the other side of the shelf 7. The tubular shaft 125 carries two doctor rolls 129—130 which are adapted to be brought in contact with the pick-up roll 104 and thereby be coated with cement so that the doctor rolls may transfer the cement to a suitable applicator head. The sleeves 116—117 are connected by links 131—132 with arched arms 134—135 that are secured to a side shaft 136 mounted on the left side of the front main frame 1 (Figs. 4 and 5). This side shaft 136 carries an arm 137 which is connected by link 138 to the universal joint 139 which is mounted on the belt crank 140 that carries an anti-friction roll 141, which is held in contact with the cam 142 by means of the long coiled spring 144. The cam 142 is mounted upon a gear 145 carried by stub shaft 146 and cooperating with the pinion 147 mounted on the main shaft 5. It will be observed that the gear 145 is twice the diameter of the pinion 147 so that when the main shaft

makes two revolutions, the gear 145 will have made but one revolution; and the cam 142 through the several connected levers, links, and arms will have caused the doctor roll carriage to have made but a single cycle 70 of operations for two cycles of the main shaft 5.

A vertically slidable shaft 148 (Figs. 1, 4, and 6) is mounted for vertical movement in the arch frame 102 and carries on its lower end a cross-bar 149 upon which are adjustably and removably mounted applicator head members 150—151. These members are constructed to be replaced and adjusted to suit various types and sizes of envelope blanks 80 and liners. The end faces of these applicator head members are adapted to be cement covered and to transfer the cement to the top blank X on the stack A of envelope blanks. The vertically slidable shaft 148 carries a cross head 152 which prevents the shaft 141 from rotating and at the same time forms a connection for a link 154 (Fig. 6) which is secured at its other end to arm 155 upon the shaft 156 (Fig. 1). The shaft 156 is mounted in bearings 157 supported by the arch frame 102 and at its left end (Fig. 4) carries a crank arm 158 to which a resilient pitman is connected. The resilient pitman comprises a looped link 159 which is connected to crank arm 158 at one end and is provided with a sleeve 160 on the other end. A rod 161 extends through the sleeve 160 and carries upon its upper end a nut 162 which is adapted to compress a spring 164 against the end of the sleeve 160. A stop collar 165 limits the slidable movement of the rod 161 in an upward direction through the sleeve 160. This rod 161 is connected to a contact arm 166 carrying anti-friction roller 167 that is held in engagement with the cam 168 on the main shaft 5, by means of the spring 169. A guard cam 170 surrounds a portion of the cam 168 and is spaced therefrom a distance substantially equal to the diameter of the anti-friction roller 167. This portion of the cam is so constructed that the guard cam may positively pull the rod 161 downward so that when the applicator head meets resistance in its downward movement, (as when it contacts with the blank X) the spring 164 may yield to allow the rod 161 to slide through the sleeve 160. This permits the faces of the applicator head members 150—151 to be tightly brought against the topmost blank 110 X of the stack A to transfer cement thereto to form cement spots 171.

Blank feeding mechanism.

The stack of envelope blanks A is definitely positioned over the shelf 7 by means of guide posts 201 which contact with the front shoulders 202 on the envelope blanks and by rear guide posts 204 which contact with the rear shoulders 205 on the envelope blanks of 130

the stack A. These guide posts 201—204 are provided with slots through which stub bolts 206 extend to adjustably mount the guide posts upon the front bed plate 12 so that the position of the guide posts may be changed when various sizes and types of envelope blanks are used in the machine. The 5 guide posts (Fig. 4) extend vertically along the shoulders of the blanks in the stack and are stationary, so that a stack of envelope 10 blanks is raised or lowered within these stationary guides as the machine operates. Since the top of the front guides are slightly above the topmost blank on the stack A, it is necessary that the topmost blank be raised 15 slightly in order to be fed through the machine.

A pair of suction boxes 207 and 208 are mounted on a cross bar 209 in such manner 20 as to leave a free central space between the suction boxes. The cross bar 209 is carried upon vertical rods 210—211 which slide through bearings in the front bed plate 12. The lower ends of these rods are connected 25 by another cross bar 212 to which a lever 214 (Fig. 2) is connected by link 215. This lever is attached by connecting rod 216 to an oscillating arm 217 carrying anti-friction roller 218 that travels upon cam 219 secured 30 to the main shaft 5. A spring 220 connected with the oscillating arm 217 holds the anti-friction roller 218 in contact with the cam 219.

It will now be observed that the operating 35 dog lever 29 for the dog 26, which controls the feed of the stack of envelope blanks, is held in contact with the under portion of the cross bar 212 by means of the spring 221, so that as the cam 219 operates to raise and 40 lower the cross bar 212 and the connected mechanism, it also oscillates the dog operating lever 29 to control the effective operation of the dog 26 on the rack 25. When the cam 219 operates to raise the oscillating 45 arm 217 and thereby lower the cross bar 212, the dog 26 is withdrawn from the rack 25 so that the springs 18 and 19 operate to raise the topmost blank X tightly against the suction boxes 207—208. This thrust of 50 the springs 18 and 19 on the suction boxes 207—208 is supported through the connecting parts directly upon the cam 219. As the cam continues to revolve and the oscillating arm turns counter-clockwise (Fig. 2) 55 thereby raising the cross-bar 212 and connected parts, the dog 26 again comes into contact with the rack 25. However, it will be observed that the upward limit of movement of the column 9 carrying the shelf 7 60 was limited by the pressure of the topmost blank X in the stack A against the end surfaces of the suction boxes 207—208. This construction therefore provides an automatic feed for the stack, which feed is controlled 65 by the upper limit of movement allowed to

the top blank on the stack, as distinguished from mechanisms of the prior art wherein the height of the topmost blank of a stack initiated or controlled lifting mechanism which operated to raise the topmost blank 70 into the zone of a feeler finger that stopped raising action.

After the applicator head members 150—151 have descended against the topmost blank, and have transferred cement thereto 75 to form cement spots 171 (Fig. 5) to the blank, the suction boxes 207—208 descend to contact with the forward edge of the topmost blank and then the applicator head rises. As the suction boxes 207—208 move 80 downwardly toward the topmost blank on the stack, suction is rendered effective through these boxes by the cam 222 (Fig. 29) which operates on a suction control valve 224 to open a line 225 leading to a suction main line 226. This causes the topmost blank to be tightly pressed against the under surface of the suction boxes 207—208 by atmospheric pressure. The cam 219 (Fig. 2) 85 now operates to raise the suction boxes 207—208 and the stack of blanks follows the upward movement of the suction boxes a short distance until the dog 26 is permitted by the upward movement of the lever 29 to drop in between the teeth on the ratchet rack 25, at which time the upward movement of the stack of blanks stops while the continued movement of the suction boxes 207—208 90 lifts the front edge of the topmost blank 95 from the stack. When this occurs, the blast of air from the jet 227 flows beneath the raised blank X and tends to float the same from the stack A. As the suction boxes 207—208 continue to raise the topmost blank, this blank is brought against the under side 100 of a suction head 228 (Figs. 4, 10, 12 and 29) which is provided with a suction conduit that terminates in downwardly directed suction openings. Prior to the contact of the raised sheet with the suction head 228, a 105 suction line 229 (Fig. 29) has been opened by a cam 230 operating upon a suction control valve 231 to connect this line with the main suction line 226. This causes the blank 110 to be pressed by a quick snap action against the suction head 228. In the meantime, just after the blank X has been pressed against the suction head 228, the valve 224 controlling the suction boxes 207—208 has been 115 operated by cam 222 to close the suction line 225 and open the same to atmosphere through a conduit 232 in the back of the valve 224.

The blank X has now been raised from the stack A and is held by the suction head 228. This suction head 228 is mounted upon a carriage 234 (Figs. 1, 10, 11 and 12) which is slidable longitudinally of the machine in guide rails 235—236. This carriage is connected at each side by links 237—238 with operating arms 239—240 mounted upon the 120 125 130

cross shaft 241 which carries a connecting arm 242 connected to pitman link 244 (Figs. 1, 3, and 9). The cross shaft 141 also carries a spring arm 245 to which a coiled spring 5 246 is attached and causes an anti-friction roll 247 to be tightly pressed against a cam 248 which is mounted on the main shaft 5. The pitman link 244 is provided with a bifurcated lower end 249 which slides over the 10 main shaft 5 as a guide. Also, this pitman link 244 is screw threaded where the upper end thereof enters the bifurcated end 249 in order that the zone of operations of the carriage 234 may be adjusted. The turning of 15 the main shaft 5 rotates the cam 248 and through the connected parts causes the operating arms 239—240 to oscillate, thereby causing the carriage 234 to have a longitudinally reciprocatory motion over the 20 machine so that the suction head has a to and fro motion from over the stack of blanks to a position over the machine. As the carriage 234 has moved rearwardly, the suction head carries the blank X with it until the shoulders or edges of the blank have been drawn under curved ends on guide rails 250—251. These guide rails are provided with anti-friction balls 252. These rails 250 and 251 provided with the curved front ends and 25 carrying the anti-friction balls, 252, are located directly above conveyor tapes 254 and 255 which run over a driven conveyor roll 256 and an idler conveyor roll 257, located about the center of the machine. Travelling 30 tapes 258 are also carried upon the driven conveyor roll and extend the full length of the machine to and over the driving tape roll 259. The lower run of the travelling tapes 258 travels over a tape tightener roll 40 260. The conveyor tapes 254 and 255 are held up tightly against the anti-friction balls 252 by means of supporting plates 261—262 which extend beneath the side rails 250—251.

As soon as the blank X has been pulled 45 into the machine beneath the anti-friction balls 252 and above the conveyor tapes 254—255, the blanks are gripped between these anti-friction balls and the conveyor tapes and are pulled forward rapidly. This 50 tight gripping action holds the blanks flat with the central portion of the blanks held up by the travelling tapes 258 so that the blanks do not tend to curl up due to air friction against the front edge of the blanks. 55 As soon as a blank has been gripped by the conveyor tapes, so that this conveyor mechanism has control of the movement of the blank, the cam 230 operates the valve 231 to shut off suction from the suction head 228 60 and to open this line to atmosphere so that the blank is quickly released from the head 228 and moves forward without any obstruction. The reciprocating movement of the carriage 234 is timed with the movement of

the cement applicator heads 150—151 and 65 with the movement of the suction boxes 207—208 so that each time a blank X is lifted from the stack A, this blank is caught by the suction head 228 and pulled into the machine. As soon as one blank is released, 70 the carriage 234 again moves forward to pick up the next blank and pull it into the machine and so on.

Figs. 13, 14 and 15 disclose a modification wherein gripping mechanism is substituted 75 for the suction head 228. This gripping mechanism comprises an anvil 264 attached to the front portion of the carriage 234 and carrying a pair of overthrow gripper fingers 265—266. These fingers are mounted upon a gripper shaft 267 and preferably each finger is allowed a slight independent movement relatively to the shaft, so that when the shaft 267 has been turned sufficiently by the crank 268, link 269, and control arm 270 80 to cause an overthrow spring 271 to act, the gripper fingers are quickly snapped to either opened or closed position. The slight loose action permits each gripper finger to independently seat against the face of the anvil 90 264. This construction is such that as the carriage 234 moves toward the front of the machine, the nose of the anvil 264 slides under the forward edge of the sheet and the control arm 270 strikes a stop (not shown) 95 which moves the arm to full line position (Fig. 14) thereby shoving forward on the link 269 and oscillating the crank 268 to turn the shaft 267 and permit the overthrow springs 271 to snap the gripper fingers closed as shown in Fig. 15. The movement of the carriage 234 toward the rear of the machine causes the control arm 70 to strike a rear stop (not shown) and reverse the movement of the parts so that the shaft 267 100 is rotated to open the gripper fingers and to permit the blank to come under control of the conveyor tapes. In this mechanism, the movement of the carriage 234 must be slightly faster than the movement of the conveyor tapes at the moment when the gripper fingers are opened in order to enable the anvil nose to be pulled out from under the blank so that the blank may be fed forward. In 105 the preferred form comprising the suction head 228, this difficulty is obviated because the sheet slides forward from the suction head 228 without meeting any obstruction and there is no part requiring to be quickly pulled out of the way of the forward travelling of the blank.

Blank positioning mechanism.

The cement spotted or wet gummed blank X is carried rapidly through the machine by 125 conveyor tapes 254—255 to an assembly table 301. (Figs. 1, 2, and 29.) The idler conveyor roll 257 is located adjacent the

front edge of the assembly table and the conveyor rails 250—251 terminate over the idler roller 257 so that the positive forward travel of the blank X terminates before the assembly table is reached and the blank is carried forward from thereon by momentum and by means of the travelling tapes 258 upon which the blank X rests. A pair of positioning pins 302—304 are adjustably mounted upon carrying arms 305 which are also adjustably mounted on a pin operating shaft 306 in such manner that the positioning pins 302 extend upwardly through openings in the assembly table 301 into the path of the front shoulders 202 on the blank X. This definitely positions the blank over the assembly table and stops its forward movement so that the travelling tapes 258 slide idly beneath the blank in grooves or troughs in the assembly table 301. The pin operating shaft 306 carries a crank arm 307 which is connected by a link 308 with a lever 309 carrying an anti-friction roller 310 which is held in contact with a cam 311 by means of a spring 312. The cam 311 is mounted upon a cross shaft 314 carried by the rear main frame 2 and on the left hand end (viewing the machine from the front), this shaft carries a sprocket wheel 315 which is driven by a chain belt 316 that runs over a driving sprocket 317 upon a main valve shaft 318. (Fig. 2.) This main valve shaft is driven from the main shaft 5 by a chain drive 319 which extends over a small sprocket 320 on the main shaft 5 and a larger sprocket 321 on the main valve shaft 318.

When the cam 311 is operated through the connected parts to cause the positioning pins 302 to stop a blank X over the assembly table, a cam 322 (Figs. 1 and 29) is operative upon a table suction control valve 323 to open a table suction line 324 to the main suction line 226 thereby rendering suction effective through four table suction openings 325. The blank X therefore is now tightly pressed against the assembly table by atmospheric pressure and is ready to receive the envelope liner.

The assembly table 301 is mounted to have a slight vertical movement and is guided by depending slotted arms 326 (Fig. 3) which slide over stub bolts 327 on vertical guide arms 328. Springs 329 (Fig. 2) tend to lift the assembly table 301 to its upper limit of movement.

The shaft 314 carries a sprocket 330 (Figs. 2, 16 and 17) which connects by drive chain 331 with sprocket 332 secured to gear 334. This gear 334 meshes with a second gear 335 attached to sprocket 336 that carries a second drive chain 337 which leads to sprocket 338 on the shaft of the tape driving roll 259. The drive just described transmits power from the main shaft 5 to the tape driving

mechanism and changes the direction of rotation to meet the requirements. 65

Liner supports.

The present machine is provided with a double liner feed, that is, liners are arranged 70 in stacks on each side of the longitudinal path of the envelope blank, and liners are fed in alternation first from the one stack and then from the other to the continuous series of blanks positioned on the assembly 75 table.

The support for the stacks of liners is substantially the same for each stack and therefore so far as parts are duplicates, they will be given the same reference characters for 80 each stack. The liners are arranged in one stack B at the left of the machine (Fig. 1) and in another stack C at the right of the machine. These stacks are respectively supported upon shelves 401, which are mounted 85 upon vertically movable columns 402 (Fig. 16) that are slidable through guiding sleeves 404 which are carried by the rear main frame 2. The columns 402 are each provided with ratchet racks 405, with which holding 90 pawls are adapted to cooperate. Coiled tapered springs 406 are mounted on rocking bases 407 carried upon brackets 408 supported upon the rear main frame 2. These coiled springs cooperate with guide stems 409 that 95 are attached to levers 410 connected by links 411 to the supporting shelves 401. The effective strength of the springs is sufficient to overcome the weight of the shelves 401 and connected parts including the weight of 100 the respective stacks of liners, so that these springs exert a pressure tending to move the stacks of liners. This pressure is resisted by the pawls referred to, engaging the racks 405. Pawl levers 412 are carried by the 105 guiding sleeves 404 and release the pawls from the racks 405 so that the springs 406 are free to lift the stacks of liners. The limit of this lifting action by the springs 406 is determined by liner holding pads 414. 110 These pads are on the ends of arms 415 carried upon shafts 416 which are provided with crank arms 417 that are connected by links 418 with bell cranks 419 and 420. The bell crank 419 is mounted upon an oscillating 115 shaft 421 and is connected by a transverse link 422 with the bell crank 420, so that as the oscillating shaft 421 is oscillated, movement is communicated to the bell cranks 419—420 and this movement is such that as the liner holding pad on the right of the machine (Fig. 16) rises, the one on the left descends. The shaft 421 carries an upwardly extending arm 424 (dotted lines Fig. 7) 120 which is adapted to engage the left hand side pawl lever 412 to release the pawl from the rack 405 when the corresponding liner holding pad 414 has reached its limit of

125

downward movement, which is substantially a horizontal position above the stack of liners B. As soon as the rack 405 is released, the tapered spring 406 of this group of mechanism raises the topmost liner into contact with the liner holding pad. The oscillating shaft 421 carries a short arm 425 to which is connected a slideable rod 426 provided with an operating finger 427. As the oscillating shaft 421 turns counterclockwise, (Fig. 16) the short arm 425 and slideable rod 426 causes the operating finger 427 to contact with the right hand pawl lever 412 thereby releasing the rack 405 to permit upward movement of the stack C of liners. At this time, the right hand liner pad 414 has descended and the topmost liner is brought against this holding pad.

The oscillating shaft 421 carries a crank 428 (dotted lines Fig. 16) which is connected by link 429 and is provided with a universal joint 430, to an eccentric 431; the rotor 432 of which is mounted upon the main valve shaft 318. The bottom portion of the columns 401 are each provided with shock absorbing pads 434 which take up the shock when the final limit of upward movement of the shelves is reached. Liner guides 435 are mounted stationary on the rear bed plate 436 and preferably are substantially square in form (Figs. 7 and 8). The guides 435 are provided with a circular stud 437, which sets in an opening in a base 438. A holding screw 439 prevents rotation of the guides 435 from a set position. The guides may be brought into a rough adjusted position by sliding the base 438 on the stud bolt 440 in a slot 441. Final adjustment is made by rotating guides 435 (as indicated in dotted lines Fig. 7) and then clamping the guide in a rotated adjusted position by the holding screw 439.

Liner carrier rolls and assembly mechanism.

A pair of guide rails 501 are mounted transversely of the machine and extend past the liner shelves 401 carrying the stack of liners B and C. (Figs. 1, 2, 3, and 16.) These rails comprise the support for a carriage 502, slidably mounted upon the rails. The carriage 502 is connected by links 504 with arms 505 mounted upon the oscillating shaft 421. When the shaft 421 oscillates the arms and connected parts cause the carriage 502 to reciprocate back and forth across the machine. A pair of liner carrier rollers 506 and 507 are mounted on the carriage 502 and are spaced apart a distance relative to the stacks of liners and the assembly table 301 so that when one of the rollers is in its extreme position toward its side of the machine, the other of the rollers has moved partly over the assembly table. These liner carrier rollers are substantially identical in construction and comprise

(Figs. 24 to 28) a cylinder of wood or other suitable material provided with recesses 508 and 509 adapted to enable the roller to pass over upstanding projections which normally are in its line of travel, such as for example, the positioning pins 302, or the liner guides 435, or similar projections. A portion of the shafts 510 of these rollers is hollow and are provided with suction conduits 511 leading from the hollow shafts to the surface of the rollers. The hollow shafts are connected by tubing 512 and 514 (Fig. 16) with the main suction conduit 226 through suitable control valves (Fig. 29). The suction on the roller 506 is controlled by cam 515 which operates on valve 516 and the suction on the carrier roller 507 is controlled by cam 517 which operates on valve 518. Both of these cams 515 and 517 are mounted upon the main cam valve shaft 318.

A gear rack 519 extends parallel to the rear guide rail 501 and the shafts 510 for the liner carrier rollers are provided with gears 520.

These gears 520 mesh with driving gears 521 mounted on the carriage 502 and in mesh with the gear rack 519. As the carriage 502 is reciprocated on the rails 501, the gearing just described causes the liner carrier rollers 506 and 507 to rotate. This rotation is such that the lower portions of these rollers travel at substantially a translatory speed equal to the linear travel of the axes of the rollers. In other words, the rotation of these carrier rollers is in the same degree and amount as if these rollers were rolling upon a flat surface. This causes the recesses 519 to always coordinate with the projections over which the recesses must pass and likewise coordinates the suction conduits 511 with the work they have to do. When the liner carrier roller 506 reaches the extreme right limit of travel, indicated by dotted lines in Fig. 16, the suction conduits 511 of this liner carrier roller 506 are directly over the outer edge of the topmost liner in the stack B. The other roller 507 has traversed the assembly table 301 slightly beyond the middle thereof. The cam 515 now operates valve 516 in such manner that suction is effective through the conduits 511 in the roller 506. This causes atmosphere to tightly press the outer edge of the topmost liner against the carrier roller 506. The carriage now reciprocates to the left (Fig. 16) and the topmost liner is wrapped around the carrier roller 506 which continues to rotate with the liner thereon and it sets this liner Y in a definite position upon blank X which is being held on the assembly table by the suction effective at the openings 325 extending through the assembly table. The roller 506 tightly presses the liner Y it is carrying against the cement spots 171 on the blank X to an extent of substantially one-half the

width of the liner. The action of the rapid movement of the roller 507 when it is stopped over the assembly table, is to whip off the unattached portion of the liner that was merely wrapped around the roller and to throw it quickly against the blank X. As soon as the initial contact edge of the liner has touched a cemented blank, cam 515 has again operated valve 516 to shut off suction from the roller 506 and to open the line to atmosphere. This releases the liner from the roller and permits the roller to roll forward without picking up the liner and to act as a squeegee roll over substantially one-half the area of the liner, which is sufficient to accurately position the same on the blank. The springs 529 under the assembly table 301 have yielded slightly to the rolling pressure of the roller 506 and has squeezed a portion of the liner and blank tightly together. In the meantime, the roller 507 reaches its extreme outward left position over the stack of liners C and cam 517 has operated to open the suction line to this roller to pick up a liner and deposit it upon the next blank X that is positioned on the assembly table 301 in the same manner that the liner was positioned by the roller 506. The rollers alternately feed liners from stacks B and C to the blanks as the carriage 502 reciprocates on the rails 501.

As soon as a particular roller 506 or 507 comes over the inner edge of the stack of liners, the respective liner holding pad 14 for this particular stack starts to raise and gets out of the way so that the roller may proceed to roll over the stack of blanks. Prior to the roller completely leaving the stack of blanks on its return movement, the holding pad is in horizontal position over the stack of blanks. This relation of movement between the respective rollers and the respective holding pads is such that the blanks in the stacks are under control at all times so that there is no danger of the liners being accidentally mussed up or carried from the stacks.

Squeegee rolls.

As soon as the liner Y has been applied to the blank X on the assembly table and the carrier roll which brought the liner Y to the assembly table has moved off of the assembly table, the positioning pins 302 descend and the cam 322 has operated the valve 323 to shut off suction and open the line to atmosphere so that the travelling tapes 258 carry the assembled blank and liner, X-Y, forwardly and delivers the same over guide wires 601 to squeegee rolls 602 and 604. The lower squeegee roll 604 is driven at a relatively high rate of speed by chain drive 605 which runs over a small sprocket 606 on the shaft of squeegee roll 604 and over a large sprocket 607 on the shaft of the driving tape

roll 259. The upper squeegee roll 602 is merely an idler and the action of these squeegee rolls is to drive the assembled unit through the squeegee rolls by applying power to the envelope blank and permitting the upper roll 602 to merely roll along over the liner, thereby tightly compressing the liner to the blank without sliding one upon the other and delivering the finished product to the delivery box 618 beneath the hold-down wire 609.

Operation.

The operation of the machine (leaving out reference to the modified form of sheet feeding mechanism comprising the double gripper) may generally be described as follows: A stack of envelopes is arranged upon the supporting shelf 7 (Figs. 1, 2, 3, 4, and 5) and stacks of liners B and C are arranged upon the liner shelves 401. The machine is thrown into operation by the manually controlled clutch 6 and the various mechanisms are thereby caused to function through the main shaft 5. The pick-up roll 104 will rotate and become covered with mucilage or cement and the doctor rolls 129 coming in contact therewith will be coated with cement. These rolls are then caused to reciprocate by the sleeves 116-117 being slid on the guide rails 118-119 by the operation of the cam 142 through the various connecting links comprising arched arms 134 etc. and the doctor rolls will pass beneath the applicator head comprising members 150-151 to transfer cement to the work faces of the head. The vertically slideable shaft 148 carrying the applicator head members 150-151 is caused to descend by the operation of the cam 168 operatively connected thereto by means of the resilient pitman comprising the looped link 159 and rod 161 and the shaft 156 which is connected with the vertically slideable shaft 141 carrying the applicator head. The downward movement of the cement applicators results in cement spots 171 being printed upon topmost envelope blank X.

As the cement applicator head has been descending, the suction boxes 207-208 have likewise been brought down by the action of the cam 219 through connected parts and suction has been rendered effective on the suction boxes by the action of cam 222 on the valve 224 so that when these suction boxes contact with or approach near to the topmost envelope blank X, atmospheric pressure tightly clamps the blank X to the suction boxes. The descent of the mechanism comprising the cross bar 212 for the suction boxes has released the holding dog 26 from the ratchet teeth 25 on the column 9 supporting the envelope shelf and has enabled the springs 18 and 19 to raise the stack A of envelopes upwardly against the suction

boxes. The applicator head rises faster than the suction boxes and thereby pulls free from the envelope blank X. As the suction boxes rise, the stack of blanks A tends to rise with them, but the upward movement of the bar 212 has caused the lever 29 to permit the dog 26 to again come into engagement with the ratchet teeth 25 and the stack of envelopes is therefore restrained from being further raised by the springs 18 and 19. A blast of air is released through the air jet 227 (Fig. 12) and floats the cement spotted envelope X from the stack. The carriage 234 has moved the suction head 228 forward so that it occupies a position over the middle portion of the front of the raised envelope blank and cam 230 operating upon control valve 231 has opened the line leading to the suction head to render suction effective thereon so that the blank is now also tightly attached by atmospheric pressure to the suction head 228. The suction effective on the suction boxes 207-208 is now cut off by the operation of cam 222 upon the valve 224 and this line opened to atmosphere so that the blank is now released from the suction boxes and is held entirely by the suction head 228.

The carriage 234 for the suction head 228 now moves rearwardly under the action of the arms 239-240 which are mounted on a cross shaft 241 and which is oscillated by the cam 248 through suitable connections. This action pulls the envelope blank X beneath the guide members 250-251 provided with curved front ends (Fig. 12) so that the edges of the blank X are clamped between the anti-friction balls 252 and the conveyor tapes 254-255. These tapes carry the blank forward to the front edge of the assembly table 301, and the traveling tapes 258 and the momentum of the blank carry the blank over the assembly table where it is accurately positioned by the positioning pins 302 contacting with the front shoulders 202 on the blank X. The blank is held in position on the assembly table 301 by suction being rendered effective through the operation of the cam 322 upon valve 323 that controls the line 324 to the table suction openings 325.

Assuming the liner carrier roller 506 to be in its extreme outward position (dotted lines Fig. 16) over the stack of liners B and that suction is rendered effective on this roller by cam 515 operating on valve 516. This suction causes the outer edge of the top liner Y to be pressed against the carrier roller 506. The carriage 502 is now pulled across the machine by the lever arms 505 which are mounted upon the oscillating shaft 421 (Figs. 3 and 16). This oscillating shaft is driven by the eccentric 431, the rotor 432 of which is mounted on the main valve shaft 318. Suction is retained on the

carrier roller 506 during its travel to the right (Fig. 16) so that the carrier roller wraps a liner Y around its periphery and proceeds on its travel toward the assembly table 301. The parts are so timed and positioned that the edge of the liner held against the carrier roller 506 by suction comes into place exactly over the cemented spotted blank X held on the assembly table. As soon as the carrier roller has caused the liner Y to contact with the cement portions on the blank X, the cam 322 operates on valve 323 to cut off suction to this carrier roller 506 and to open this suction line to atmosphere. This releases the liner Y from the carrier roller 506 and the carrier roller continues to proceed to a distance slightly beyond the middle of the assembly table. The springs 329 beneath the assembly table form a resilient cushion to press the assembly table upwardly toward the carrier roller 506 so that the liner Y is pressed against the cement spots 171 on the blank X sufficiently to cause the liner to tightly attach itself to the blank and in exact register therewith.

In the meantime, as soon as the carrier roller 506 left its position over the stack of liners B, the corresponding holding pad 414 descended over this stack of liners B and the operating finger 427 on the slidable rod 426 has contacted with the pawl lever 412 to release the rack 405 and permit the spring 406 to raise the stack of liners B upwardly until the topmost liner is against the liner holding pad 414, thereby automatically feeding the stack upwardly as the liners are taken from the top thereof.

As the carrier roller 506 moved over the assembly table, its companion carrier roller 507 moved over the stack of liners C and when the carrier roller 506 reached its extreme limit of travel to the left, (Fig. 16) its companion liner carrier roll 507 reached its extreme left position over the stack of liners C with the suction openings in the roller over the outer edge of the topmost blank of the stack C. The cam 517 is now effective to open the suction line leading to the roller 507 by opening the valve 518 and the outer edge of the topmost liner in the stack C is now attached to the carrier roller 507. As the carriage 502 is returned to the right (Fig. 16) carrier roller 507 picks up the topmost liner Y from the stack C and carries the same to the next envelope blank X which has been positioned on the assembly table 301; and the operations with reference to the stack of blanks C and the transfer mechanism is a repetition of those movements and functions which have been described relative to the carrier roller 506 and connected parts. This alternating action of taking a liner first from stack B and second from stack C thereby alternating the opera-

tion of the carrier rollers, greatly speeds up the operation of the machine.

Coming back now to the next step relative to the blank which was on the assembly

- 5 table 301 and which had received a liner Y from carrier roller 506, the positioning pins 302 have been moved downwardly (Fig. 2) by the operation of cam 311 through connected parts and suction on the table openings 325 has been cut off by the operation of cam 322 upon valve 323 so that the travelling tapes 258 carry the combined blank and liner X-Y rapidly to the squeegee rolls 601--602 at the rear end of the machine.
- 10 15 The combined unit X-Y passes through these rolls with the bottom squeegee roll 601 acting as a driving member and the upper squeegee roll 602 acting as a pressure member to tightly squeeze the liner Y against the blank X, thereby spreading the cement between the two and causing the cement to enter between the paper fibers and cement the two sheets of paper together. The unit X-Y leaves the squeegee rolls and drops
- 20 25 30 into the delivery box 603 as a finished product or where desired, the unit X-Y may be conveyed directly to the feeding mechanism of an envelope forming machine (not shown) where envelope forming operations take place.

Having thus described my invention, what I claim is:

- 1. A machine for assembling sheet blanks comprising means to support a stack of blanks at one end of the machine, devices to move blanks individually from said stack through said machine, mechanism for supporting a plurality of stacks of other blanks adjacent the path of movement of the first mentioned blanks, and devices to feed said other blanks one at a time from said plurality of stacks in serial order from said stacks whereby a single one of said other blanks is fed for each blank fed from said first mentioned stack.

- 2. A machine for assembling blanks of sheet material comprising means to support a stack of blanks, devices to feed individual blanks from said stack and move the same through the machine, means to support a plurality of stacks of other blanks with the path of movement of the first mentioned blank passing between stacks of said other blanks, and devices to feed said other blanks from a stack on one side of said path and then from a stack on the other side of said path, there being one of said other blanks fed for each blank fed from said first mentioned stack.

- 3. A machine for assembling blanks of sheet material comprising in combination means to support a stack of blanks, an assembly station, devices to feed blanks from said stack to said assembly station, means

to support two stacks of other blanks, mechanism to feed said other blanks to said assembly station in such manner that said other blanks are fed in alternation from the said two stacks of other blanks.

4. A machine for assembling blanks of sheet material comprising in combination means to support a stack of blanks at one end of a machine, feeding and conveyor mechanism adapted to feed blanks one at a time from said stack and to convey the same as a continuous linear series through said machine, means to support a pair of stacks of other blanks, said linear path for the first mentioned blank passing between said pair of stacks (mechanism to feed said other blanks from said pair of stacks in alternation, there being one of said other blanks fed for each of said first mentioned blanks,

5. In a machine for assembling blanks of sheet material, the combination of means to feed a series of blanks to an assembly station one at a time, devices to hold a single blank at said station while more of said blanks are being fed toward said station, suction devices to feed other blanks to said assembly station and superimpose the same upon the blank held thereon, said suction devices operating to bring said other blanks to said assembly station first from one side thereof and then from the other side thereof,

6. A machine for assembling blanks of sheet material comprising in combination an assembly station, means to feed a series of blanks one at a time to said assembly station, means to stop and hold said blanks individually at said assembly station, devices located at one side of the machine to feed other blanks to a series of alternate first mentioned blanks as they are held at said assembly station, and devices located upon the opposite side of said machine to also feed other blanks to the remaining series of first mentioned blanks as they are held at said assembly station.

7. A machine for assembling blanks of sheet material comprising in combination means to supply cement to a blank, devices to feed said cement carrying blank through the machine, and rolling means to accurately position another blank upon said first mentioned blank over said cement covered areas and apply pressure to said blanks over a portion only of said cemented areas.

8. In a machine for assembling blanks of sheet material, the combination of means to apply cement to a blank, devices to feed said cement carrying blank through a machine, rolling devices to carry another blank over said cement carrying blank and position the same in a predetermined relation thereto over the cement covered area and apply pressure to said assembled blanks over a portion only of the cement covered area, and means to apply pressure over the entire area of both of said assembled blanks.

9. In a machine for applying liners to envelope blanks, means to support a stack of envelope blank members, an assembly table, means to individually convey said blanks to said assembly table, mechanism to position said blanks upon said assembly table, devices to feed liner members to said assembly table and assemble the same over a blank member, there being one liner fed for each blank positioned thereon, devices to apply cement to one of said members, and resilient means to apply pressure to a portion of said assembled liner and blank while on said assembly table.
10. A machine for assembling envelope blanks and liners therefor comprising an assembly table mounted to yield against pressure applied thereto, means to feed envelope blank members one at a time to said table, devices to apply a liner member to each blank fed to said assembly table and assemble the same upon a blank thereon, means to apply cement to one of said members, and means to cause pressure to be applied to the assembled members at the assembly table over a portion of the cemented area.
11. In a machine for assembling envelope blanks and liners, the combination of means to apply cement to portions of the envelope blanks, an assembly table supported upon springs, means to convey said cement coated blank to said assembly table, and means to apply a liner to the blank on the assembly table and to apply pressure to the assembly table over a portion of the liner positioned over the said cement to secure such portion of the liner to the blank.
12. A machine for carrying out steps in the manufacture of envelopes comprising a table to support a stack of sheets of paper, stop means to limit upward movement of said table, means to bias said table upwardly against the action of said stop means, adhesive applying means operable to apply adhesive to the uppermost sheet of paper in the stack, means to depress said adhesive applying means toward the uppermost sheet of paper, and means to disable said stop means for an interval whereby the stack is moved upwardly to press the uppermost sheet against the adhesive applying means.
13. The method of assembling blanks of sheet material comprising feeding blanks from a single stack, and then feeding other blanks from a plurality of stacks of other blanks in series from the stacks of said other blanks in such manner that one of said other blanks is superimposed upon each of the first mentioned blanks so that when a number of said first mentioned blanks have been fed equal to the number of stacks of said other blanks, each of said stacks of said other blanks is diminished by one of said other blanks.
14. The method of applying liners to envelope blanks comprising feeding a series of envelope blanks one at a time to an assembly table, feeding liners from opposite sides of said assembly table and in alternation, and superimposing said liners upon said blanks.
15. The method of assembling envelope blank members and liner members comprising applying cement to one of said members, positioning the other of said members over said cement covered area, applying rolling pressure to a portion only of the assembled members over a portion only of the cement covered area to secure the members in register, and then applying pressure over the entire surface of the said assembled members.
16. The method of assembling envelope blank members and liner members therefor comprising applying cement to one of said members, positioning the other of said members over the cement covered area, applying rolling pressure to a portion only of said members and over a portion only of the cemented area to secure the members in register, and then applying rolling pressure to said assembled members over the entire cement covered area.
17. The method of assembling envelope blank members and liner members therefor comprising applying cement to one of said members, positioning the other of said members over the cement covered area, applying rolling pressure in one direction to a portion of said members and over a portion of the cemented area, and applying rolling pressure in another direction to said assembled members over the entire cement covered area.
18. The method of assembling envelope blank members and liner members therefor which method comprises applying cement to one of said members, superimposing the other of said members over the cement covered area, applying a travelling pressure to said members over a portion only of the cement covered area to secure the members in register, and then applying travelling pressure to the members over the entire cement covered area.
19. The method of assembling envelope blank members and liner members therefor which method comprises applying cement to one of said members, superimposing the other of said members over the cement covered area, applying a travelling pressure moving in one direction to both of said members over a portion only of the cement covered area to secure the members in register, and then applying travelling pressure moving in a different direction to both of said members over the entire cement covered area.
20. The method of applying a liner to an envelope blank which comprises rolling up the liner, unrolling a portion of the liner onto the blank, and permitting the remain-

der of the liner to move into juxtaposition to the blank.

21. The method of applying a liner to an envelope blank which comprises wrapping the liner against a roller, unrolling a portion of the liner onto the blank, permitting the remainder of the liner to move into juxtaposition to the blank, and rolling down the liner along lines transverse to the unrolling of the liner.

22. The method of attaching a liner to an envelope blank which comprises applying adhesive to the blank, rolling up the liner, unrolling a portion of the liner while pressing that portion against adhesive on the blank, and permitting the remainder of the liner to move into juxtaposition to the blank.

23. The method of attaching a liner to an envelope blank which comprises applying adhesive to the blank, rolling up the liner, unrolling a portion of the liner while pressing that portion against adhesive on the blank, permitting the remainder of the liner to move into juxtaposition to the blank, and rolling the entire liner against the blank to cause firm contact with all of the adhesive.

24. In a machine for assembling sheet blanks, means to hold a first blank adapted to receive a second blank, a blank applying member adapted to apply a second blank to the first blank, devices to cause a blank to be wrapped against said applying member with one edge secured to the member, and means to operate said applying member and said devices to cause the member to apply and press a portion only of the second blank against the first blank and allow the remainder of the second blank to move in juxtaposition to the first blank.

25. In a machine for assembling sheet blanks, an assembly table, means to hold a first blank on the assembly table, a blank

applying member adapted to apply a second blank to the first blank, devices to cause said second blank to be wrapped against said applying member with one edge secured to the member, and means to operate said applying member and said devices to cause the member to apply and press a portion only of the second blank against the first blank and allow the remainder of the second blank to move in juxtaposition to the first blank.

26. In a machine for assembling sheet blanks, an assembly table, means to hold a first blank on the assembly table, a blank applying roller adapted to apply a second blank to the first blank, devices to cause said second blank to be wrapped against said roller with one edge secured to the roller, and means to operate said roller and said devices to cause the roller to place said edge of the second blank in a predetermined position on the first blank and then roll a portion only of the second blank against the first blank and allow the remainder of the second blank to move in juxtaposition to the first blank.

27. In a machine for assembling sheet blanks, means to hold a first blank adapted to receive a second blank, a blank applying roller adapted to apply a second blank to the first blank, devices to cause said second blank to be wrapped against said roller with one edge secured to the roller by suction, means to operate said roller to cause the roller to position said edge in a predetermined position on the second blank and then roll a portion only of the second blank against the first blank and allow the remainder of the second blank to move into juxtaposition to the first blank, said devices being operable to release the suction as soon as said edge has been positioned on the first blank.

HENRY J. TOEPFERT.
